UNITED STATES PATENT OFFICE.

WILLIAM E. DOUGHTY, OF DETROIT, MICHIGAN, ASSIGNOR TO JAMES VERNOR COMPANY, OF DETROIT, MICHIGAN, A CORPORATION OF MICHIGAN.

METHOD AND APPARATUS FOR DISPENSING CARBONATED BEVERAGES.

Application filed June 1, 1926. Serial No. 113,056.

This invention relates to apparatus for dispensing carbonated beverages and more especially to improvements therein pertaining to agitating means employed in connection with the cooling medium for the beverage.

While the invention finds utility in dispensing apparatus of various characters and designs nevertheless it may be employed to 10 particular advantage in small portable units such as are designed to be quickly and economically manufactured and sold at a small cost for use on the counter or the like of drug stores, confectioners and other similar 15 establishments.

Apparatus of this character to be commercially successful must function to adequately cool the beverage and to maintain the desired low temperature even under conditions where the beverage is being 20 constantly dispensed. This has heretofore been accomplished with more or less success by providing a tank adapted to contain a cooling medium such as water and cracked ice 25 in which a cooling coil is immersed together with a settling chamber to which the high pressure carbonated beverage is conducted and from which the beverage is drawn as a low pressure beverage. In order that such 30 cooling means function efficiently when the capacity of the cooling coils is taxed to the limit, by reason of the beverage being constantly dispensed, agitating means are provided for circulating the cooling medium 35 and maintaining the same in a state of agitation.

Heretofore a motor-driven propeller has been employed as an agitator and while an arrangement of this character functions 40 more or less efficiently it not only adds materially to the cost of manufacture but also increases the maintenance cost. In small portable units which may otherwise be economically manufactured and operated, this 45 character of agitating means, owing to its cost, is relatively unsatisfactory.

It is, therefore an object of this invention to provide means for agitating or circulating the cooling medium without the employment 50 of exterior or added mechanism or power but to utilize the excess gas freed from the beverage and accumulated in the settling tank. To this end the invention contemplates an ejector nozzle or the like 55 submerged in the cooling liquid and suit-

ably connected by a valve controlled conduit to the settling chamber so that at intervals the gas from this settling chamber will be permitted to escape through this ejector nozzle to thereupon cause an agitation of the 60 cooling fluid.

The valve controlling the flow of this gas to the ejector nozzle may be operated in dependence upon and as a result of the operation of the beverage dispensing valve or automatically by means of a valve actuated in dependence upon the level of the beverage in the settling tank and the pressure of the accumulated gas therein. As the description of the invention proceeds it will be obvious that the passage of the gas to the ejector may be controlled in other ways as for instance solely by means of a pressure actuated valve operable in dependence upon the pressure in the settling tank.

This invention therefore also contemplates and has as one of its primary objects the provision of a unitary structure or self-contained unit which may be manufactured and shipped complete and ready for installation without necessitating the employment of outside or separate mechanism in use. This is possible because the agitating means is contained and operable from within the cooling medium container. Obviously the use of agitating means for the cooling medium, if for instance compressed air were used, would necessitate the provision, exteriorly of the unit, of a compressed air tank or compressor or both while the employment of 90 a motor-driven or other mechanically operated agitator would necessitate the employment exteriorly of the container, of mechanism for actuating the agitator. Obviously with the present invention the source of 95 power of the agitator means is arranged within the container and forms a part of the complete self-contained unit.

The invention also contemplates broadly the provision of a fluid agitator as distinguished from mechanical agitators and as stated hereinbefore proposes the use of the gas collected in the settling chamber which constitutes a suitable source of energy for this purpose which would otherwise be lost.

The invention furthermore contemplates broadly the provision of an agitator for the cooling medium which is operable at intervals without the use of complicated control means. Owing to the adherent nature of 110

- the agitator means employed this automatic control of the agitating means may be more conveniently provided for. Such an arrangement is particularly advantageous inasmuch as the cooling medium which customarily consists of water together with ice, may be more economically used inasmuch as such cooling medium is only agitated during the time the beverage or other liquid to be cooled is being withdrawn. When constantly operated agitators are employed the ice melts quicker and consequently a greater supply of ice is consumed during any given period.
- 15 Various other such objects, advantageous and novel details of construction of this invention will be made more apparent as this description proceeds, especially when considered in connection with the accompanying drawing wherein:
- Figure 1 is a view partly in vertical section and partly in elevation of a beverage dispensing apparatus constructed in accordance with this invention.
- 25 Figure 2 is an enlarged longitudinal sectional view through the valve mechanism of the apparatus.
- Figure 3 is an enlarged view of the ejector nozzle.
- 30 Figure 4 is a view similar to Figure 1 showing a slightly modified arrangement and
- Figure 5 is a fragmentary detail sectional view of the ejector control valve.
- 35 Referring now particularly to the drawing wherein like reference characters indicate like parts it will be noted that there is illustrated a tank 10 which may comprise inner and outer walls 11 and 12 arranged with in insulating medium 13 therebetween. This tank is adapted to contain a cooling medium such as water 14 and ice 15. The reference character 16 indicates a cover or closure for the upper open side of the tank
- 40
- 45 10.
- It is customary, for convenience in handling, storage and shipment, to place the beverage in tanks containing for instance ten (10) gallons, one of which tanks (not shown) will be connected to a cooling coil 17 through the intermediary of a coupling 18. Obviously the cooling coil 17 may be of any desired length and configuration and will be immersed within the cooling medium 50 contained within the tank 10. The reference character 19 indicates a settling chamber or tank into which the high pressure beverage flows from the end 20 of the cooling coil. The function of the settling chamber 55 19 is to relieve the high pressure beverage of a large amount of the gas contained therein so that when the beverage is drawn from the settling chamber it will not become unduly foamy, a condition which would result if the beverage were drawn directly from

the high pressure tank or original container. Thus the beverage flowing into the tank 19 liberates a certain amount of the gas contained therein which gas accumulates in the upper end of the tank 19.

The reference character 21 indicates generally a draft apparatus which includes a draw-off spout or nozzle 22 controlled by a valve 23 actuated by a handle 24. This draft apparatus may be provided with a tubular or sleeve-like extension 25 which extends through the wall of the tank 10 and threadedly engages a coupling sleeve 26. A packing gland 27 may be provided at the point at which the extension 25 passes through the wall 10 together with a nut 28 for holding the same in place. A pipe 29 connected to the settling chamber 19 at the bottom thereof as indicated at 30 and to the sleeve 26 as indicated at 31 provides means for withdrawing the beverage from the chamber or tank 19 to the draft apparatus.

The reference character 32 indicates a valve casing provided with a threaded portion 33 for engagement with the adjacent threaded end of a sleeve 26. The casing 32 is provided with a chamber 34 in which a valve 35 is adapted to reciprocate, this valve being normally urged against its seat 36 by means of a spring 37 bearing on the one hand against the valve 35 and on the other hand against a screw cap 38 threaded on to the end of the casing 32. A pipe or conduit 39 is connected to the chamber 34 through the cap 38 and is connected on the other hand, as indicated at 40, to the top of the settling chamber, 19. The valve 35 controls communication between chamber 34 and the bore or chamber 41 which is connected by a pipe 42 with an ejector device 43. This ejector device is in the form of a circular tube 44 provided with a plurality of openings 45 through which the gas escapes. Obviously, however, any other desired form of ejector device or discharge nozzle or nozzles may be employed. The arrangement of the parts preferably is such that the gas issues substantially in the direction of the settling tank or toward that side of the tank 10 diametrically opposed to the axis of the vent tube 44.

In this embodiment of the invention it is proposed to control the valve 35 by means of the draft valve control handle 24 and for this purpose the following construction is provided. The handle 24 which is pivoted as at 46 has its lower end 47 extending into a slot 48 formed in a sliding block 49 which carries the valve 23. A rod 50 slidably engaging the block 49 extends through a packing 51 in the valve casing 32 and through the bore 41 where it is connected to the valve 35. The forward end 52 of the rod 50 is held projected into the slot 48 by the spring 37 before referred to. It will be

noted that this slot 48 is of a greater width than the end 47 of the valve handle so that there is a lost motion connection between the handle 24 and the block 49. Thus during the initial movement of the handle 24 in the direction of the arrow A, which is the direction for opening the valve 23, the valve 23 will not be immediately opened but an independent movement will first be imparted to the rod 50 to unseat the valve 35. Obviously during a continued movement of the handle 24 both the block 49 and consequently the valve 23 as well as the rod 50 and consequently the valve 35 will move in unison. A spring 53 is arranged to normally urge the valve 23 in its closed position.

When the valve 35 is opened gas from the top of the settling chamber 15 will flow through conduit 39, chamber 34, pass the valve 35 through the bore 41 and conduit 42 to the ejector device where it will issue through the openings 45 of the nozzle 44. This will cause an agitation of the water constituting a part of the cooling medium and the circulation thus promoted effects a more efficient cooling of the beverage. Obviously by the arrangement just described this agitation of the cooling medium will commence prior to the time that the valve 23 is opened so that the circulation of the cooling medium starts before any of the beverage is withdrawn from the draw-off nozzle 22. It will furthermore be obvious that gas will continue to issue from the ejector device during the entire time that the beverage is being withdrawn as during this time the valve 35 is maintained in open position. When the handle 24 is released the springs 37 and 53 will return the valves 35 and 23 to their closed positions.

The tank 10 will preferably be provided with an overflow pipe 54 for controlling the level of the water 14 which pipe may be protected by protective screen 55.

In Figures 4 and 5 a slightly modified form of construction is illustrated in which the escape of the gas from the settling chamber is automatically controlled. Inasmuch as most of the essentials of the dispensing apparatus are similar to that previously described, only those parts which differ will now be referred to.

In this construction the end of the cooling coil 17 enters the settling tank 19 as indicated at 56 and the ejector device 43 is connected by means of a tube or conduit 57 to an automatic control device 58 connected to the settling tank 19 at the top thereof. By reference to Figure 5 it will be noted that this automatic control device involves the following construction or its equivalent. I provide a valve casing 59 formed with a gas chamber 60. The gas from the settling chamber 19 is free to pass to the chamber 32 through port 61 of plug 62, the lat-

ter having an axial bore affording a sliding bearing for valve stem 63 of a primary valve 64, the latter controlling the escape of gas from chamber 60 by way of port 65. Connected with the valve stem 63 is a float 66 whereby the primary valve 64 is controlled by the level of the settled or low pressure beverage within the settling chamber. A secondary valve casing 67 is threadedly connected as at 68 with the primary valve 64 casing, the casing 67 having an inlet port 69 registering with the port 65 affording passage for the gas from the chamber 60 to a chamber 70 in the secondary valve casing, the passage of gas thereto being controlled by a secondary valve 71 normally seated by spring 72. The gas in chamber 70 is free to escape through ports 73 and 74, the latter communicating with the pipe or conduit 57 aforesaid. The pressure of spring 72 may be regulated by properly adjusting the cap 75, forming an abutment for this spring.

With this construction the spring 72 may be adjusted to seat the secondary valve 71 whenever the pressure in the settling chamber falls for instance below two pounds per square inch. When the beverage is drawn from the settling chamber the float 66 lowers unseating the valve 64. If the pressure in the settling chamber is less than six pounds per square inch high pressure beverage will flow therein past a regulator valve 76 from the coil 17. Whenever the pressure of the beverage in the settling chamber is more than two pounds per square inch, and the valve 64 unseated, the excess pressure passes from the settling chamber to the primary valve chamber 60, past valve 64 and through ports 65 and 69 to the secondary valve chamber 70, whence it acts to unseat the secondary valve 71, the gas then passing through ports 73 and 74 and through pipe 57 to the ejector device. Thus it will be seen that the ejector device will function in dependence upon the pressure of the gas in the settling chamber primarily although this pressure is to some extent dependent upon the level of the beverage therein so that the actuation of the ejector is partly influenced by the actuation of the draft device.

From the foregoing it will be apparent that this invention contemplates the utilization of a source of energy heretofore wasted because in either of the two herein described constructions or in any substantially similar types of dispensing apparatus it has been necessary to periodically relieve the settling tank of the accumulated gas freed from the settled or low pressure beverage. Obviously with the present invention this source of energy is efficiently utilized to agitate the cooling medium to force a circulation thereof. From the foregoing description it will be apparent that the principles of the invention

tion may be embodied in different structural arrangements, two of such arrangements being shown and described herein.

Accordingly it should be understood that the invention consists broadly in conducting the excess gas freed from the settled or low pressure beverage to an ejector or agitator device employed for agitating or enforcing a circulation of the cooling medium. As the mechanical details wherein the invention is carried into execution may be varied as desired or found necessary or expedient, the illustrative embodiment of the invention herein shown and described should not be considered as limiting the scope of the invention in any particular whatsoever. Accordingly reservation is made to make such changes in the details of construction and in the manner of carrying into execution the invention as may come within the purview of the accompanying claims.

What I claim as my invention is:

1. In a carbonated beverage dispensing apparatus, a tank adapted to contain a cooling liquid, means within said tank for receiving the beverage and for collecting a portion of the gas therefrom and an agitator means for said cooling liquid actuated by said gas.

2. In a carbonated beverage dispensing apparatus, a tank adapted to contain a cooling liquid, a settling chamber within said tank adapted to receive the beverage and an agitator means for the cooling fluid operated by the gas collected by said settling chamber.

3. In a carbonated beverage dispensing apparatus, a tank adapted to contain a cooling medium, a coil for introducing a beverage to be cooled into said tank and means for ejecting gas from said beverage into said cooling medium below a portion of said coil for circulating the cooling medium around the coil.

4. In a carbonated beverage dispensing apparatus, a tank adapted to contain a cooling liquid, means for conducting a beverage to be cooled through said liquid, said means including a settling chamber in which gas from said beverage collects, a discharge nozzle below the normal level of the said cooling liquid and adjacent the said chamber and means for conducting the gas from said settling chamber to said discharge nozzle.

5. In a carbonated beverage dispensing apparatus, a tank adapted to contain a cooling liquid, means for conducting a beverage to be cooled through said liquid, said means including a settling chamber in which gas from said beverage collects, a cooling liquid agitating device including a tube provided with a plurality of spaced discharge openings arranged around said chamber and means for conducting gas from said settling chamber to said tube.

6. In a carbonated beverage dispensing apparatus, a tank adapted to contain a cooling medium, means for introducing a beverage to be cooled into said tank including a cooling coil and a settling chamber, a substantially circular discharge nozzle arranged below the normal level of said cooling medium and means connecting said nozzle to said settling chamber whereby gas freed from said beverage is supplied to said nozzle for agitating said cooling medium.

7. In a carbonated beverage dispensing apparatus, a tank adapted to contain a cooling liquid, means for introducing a beverage to be cooled into said tank including a settling chamber, a draft apparatus for withdrawing liquid from said settling chamber, a discharge nozzle extending partially around said settling chamber and automatic valve control means connecting said discharge nozzle to said settling chamber whereby gas collected in the latter may be conducted to said discharge nozzle.

8. In a carbonated beverage dispensing apparatus, a tank adapted to contain a cooling liquid, means for introducing a beverage to be cooled into said tank including a cooling coil and settling chamber, a discharge nozzle arranged below the normal level of said cooling liquid, means connecting said nozzle to said settling chamber whereby gas from said beverage collected therein may be conducted to said discharge nozzle, a combined level and pressure controlled valve for controlling said gas and a draft apparatus including a valve connected to said settling chamber.

9. The method of cooling a carbonated beverage, which consists in conducting the beverage through a cooling liquid in a tank, relieving the beverage of a portion of its gas and agitating the cooling liquid around the beverage conducting means by said gas.

10. The method of cooling a carbonated beverage, which consists in conducting the beverage in heat exchange with a liquid mixed with ice, relieving the beverage of a portion of its gas and agitating the cooled liquid by ejecting said gas therethrough.

11. In a liquid cooling apparatus, a tank for a cooling medium, a container within the tank for the liquid to be cooled and fluid means for agitating said cooling medium around the said container.

12. In a liquid cooling apparatus, a container for a cooling medium, means in the form of a conduit for introducing the liquid to be cooled into said cooling medium and means for ejecting fluid into engagement with said cooling medium around said conduit for agitating the said cooling medium.

13. In a liquid cooling apparatus, a container for a cooling medium, means in the form of a conduit for introducing the liquid to be cooled into said cooling medium and

means operable at intervals for agitating said cooling medium around said conduit.

14. The method of cooling a carbonated beverage which consists in conducting the beverage through a cooling liquid, and discharging a gas into the cooling liquid adjacent the beverage conducting means to agitate the cooling liquid.

15. In a carbonated beverage dispensing apparatus, a tank adapted to contain a cooling medium, means for conducting a beverage within said tank, and means for discharging a portion of the gas from said beverage below a portion of the said beverage conducting means for agitating the said cooling medium around the beverage conducting means.

16. In a carbonated beverage dispensing apparatus, a tank adapted to contain a cooling medium, a chamber within the said tank for receiving a beverage to be cooled and for separating a portion of the gas therefrom and a conduit connected to the upper portion of the chamber and having a portion partially encircling the said chamber for discharging the gas separated therein around the said chamber to agitate the cooling medium.

17. In a carbonated beverage dispensing apparatus, a tank adapted to contain a cooling medium, means for circulating a beverage to be cooled through the said tank including a chamber and a coil connected to the said chamber and means for circulating the cooling medium in the tank around the said coil and chamber including a conduit adapted to receive a portion of the gas from the carbonated beverage and to discharge the said gas into the tank below a portion of the said coil and chamber.

18. In a carbonated beverage cooling apparatus, a container for a cooling medium, a chamber within said container for receiving the beverage and for collecting a portion of the gas therefrom, means for discharging the gas collected in the said chamber into the lower portion of the container and into contact with the cooling medium to agitate the cooling medium and a valve operable upon a predetermined pressure of the gas within the chamber for controlling the flow of the gas through the said discharge means.

19. In a carbonated beverage cooling apparatus, a container for a cooling medium, a chamber within said container for receiving the beverage and for collecting a portion of the gas therefrom, means for discharging the gas collected in the said chamber into contact with the cooling medium around the chamber to agitate the cooling medium and a valve operable in dependence upon the level of the beverage within the said chamber for controlling the flow of gas through the said discharge means.

20. In a carbonated beverage cooling apparatus, a container for a cooling medium, a chamber within said container for receiving the beverage and for collecting a portion of the gas therefrom, means for discharging the gas collected in the said chamber into contact with the cooling medium around the chamber to agitate the cooling medium and a valve operable in dependence upon the level of the beverage within the said chamber and the pressure of the gas within the said chamber for controlling the flow of the gas through the said discharge means.

In testimony whereof I affix my signature.
WILLIAM E. DOUGHTY.
